ATTORNEY.

UNITED STATES PATENT OFFICE.

EMANUEL M. LEVY, OF BUFFALO, NEW YORK.

DESIGN FOR A BADGE.

SPECIFICATION forming part of Design No. 30,601, dated April 25, 1899.

Application filed March 20, 1899. Serial No. 709,864. Term of patent 3½ years.

To all whom it may concern:

Be it known that I, EMANUEL M. LEVY, a citizen of the United States, residing at Buffalo, in the county of Erie and State of New York, have invented and produced a new and original Design for Badges, of which the following is a specification, reference being had to the accompanying drawing, forming a part thereof, in which a plan view of my new design is shown.

As shown in the drawing, the leading feature of my design consists of a plate 1 of irregular formation shaped to represent the head of a buffalo, and a pan 2, suspended

from said plate 1 by a ring 3, passed through 15 the plate and the handle of the pan. The circular peripheral panel 4 affords a suitable space for any desired words or legends.

Having described my invention, what I claim as new, and desire to secure by Letters 20 Patent, is—

The design for a badge, as herein shown and described.

EMANUEL M. LEVY.
